(57) **CLAIM**

The ornamental design for a folding platform, as shown and described.

DESCRIPTION

FIG. 1 is a top perspective view of a folding platform showing my new design;

FIG. 2 is top perspective view of a folding platform in an alternate closed position;

FIG. 3 is a front view of a folding platform in an open position;

FIG. 4 is a rear view of a folding platform in an open position;

FIG. 5 is a front view of a folding platform in a closed position;

FIG. 6 is a rear view of a folding platform in a closed position;

FIG. 7 is a top plan view of a folding platform;

FIG. 8 is an enlarged partial upper rear left corner view of a folding platform;

FIG. 9 is an enlarged partial upper right rear corner of a folding platform; and,

FIG. 10 is a cross sectional view taken along lines 10 in FIG. 7.

The characteristic feature of the folding platform design is characterized by a safety barricade integrated into a walkway, such folding platform having open and closed phases. The distal ends of the platform are attached to vertical structural rods.

In the drawings, the broken lines depict portions of a vehicle that form no part of the claim.
